UNITED STATES PATENT OFFICE

2,476,865

PHONOGRAPH RECORD CHANGER

Earle G. Henry, Wilmette, Ill., assignor to Buckley
Music System, Inc., a corporation of Illinois

Application December 17, 1942, Serial No. 469,312

6 Claims. (Cl. 274—10)

1

The present invention has for its object to produce a simple and novel mechanism whereby any one of a plurality of disk type records may be played at will.

A further object of the present invention is to provide a simple and novel mechanism that permits a stack of records to be supported on the rotatable table of a phonograph and any record to be played while it remains on the table, with a minimum amount of movement of records incident to the making of a selection and restoring conditions as they existed at the beginning, upon completing the playing of a record.

A further object of the present invention is to produce a simple and novel record changing mechanism for a phonograph which protects the records against wear other than that which is incident to the mere playing of a record.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a top plan view of a phonograph embodying the present invention, the casing being shown in section; Fig. 2 is a section on irregular line 2—2 of Fig. 1; Fig. 3 is a section on line 3—3 of Fig. 1, some parts being shown in elevation instead of in section; Fig. 4 is a section on line 4—4 of Fig. 3, showing only a fragment of the front end of the casing; Fig. 5 is a vertical section through the tray and a record held therein; Fig. 6 is a view similar to Fig. 1, showing only a portion of the apparatus, and illustrating the parts in playing positions whereas in Fig. 1 they are in normal idle positions; Fig. 7 is a view looking diagonally at the lower left hand corner of the phonograph as it appears in Fig. 1, the casing being omitted and only a portion of the phonograph being illustrated; Fig. 8 is a view similar to Fig. 7 showing a smaller fragment of the phonograph and the tone arm being in playing position; Fig. 9 is a detail of a locking device to prevent vertical movements of the selector except when all records are in place in the stack; and Fig. 10 is a diagram of the required electrical system.

Referring to the drawings, 1 represents a phonograph turn table which, for the sake of convenience, is shown as rotatably mounted upon the outer end of a rigid bracket 2 secured to and projecting inwardly from the rear side of a suit-

2

able cabinet or casing. The table is shown as having a downwardly projecting hub 4 on the lower end of which is a gear wheel 5 that meshes with a driving pinion 6; this pinion being driven in any usual or suitable way by a motor 7.

Records of the disk type A are adapted to be individually held in light trays 8 of considerably greater depth than the thickness of a record, as best shown in Fig. 5. These trays may conveniently be formed of sheet metal so fashioned as to have thick annular walls whose tops are flat as indicated at 9. By making the annular walls thick, they will be sufficiently sturdy to permit loaded trays to be stacked one upon another and, by making the upper faces of such walls flat, wide bearing surfaces are presented for the support of overlying trays.

In accordance with my invention, a record is played while it remains in the stack, this being made possible by shifting the overlying record-carrying trays out of the way. In order to conserve space and avoid the expenditure of unnecessary energy for shifting records, I provide means which simply slide all of the trays above the one containing the selected record laterally without substantially raising or lowering them; it being unnecessary to carry them laterally any further than is necessary to enable the tone arm to swing from the periphery of the record to the inner end of the sound track, namely less than one-half the diameter of the record. While shifting a part of the trays, it is necessary that those remaining on the table be accurately centered. I have therefore provided means to accomplish this. Each tray has in the bottom a central hole 10, and each record is provided with a like hole. A bore of the same diameter as the holes 10 extends from the top of the turn table down through the hub and the gear wheel 5. Extending up through this bore and through the central holes in the trays and records, is a round stem 11, which is long enough to reach to the top of the stack. This stem is carried upon and rises from the outer end of a vertically movable arm 12, whereby the stem may be raised and lowered at will. The arm 12 is conveniently fixed to a long sleeve 14 that surrounds a vertical shaft 15, fixed within the front part of the casing not far from the stack of trays. Whenever the stem 11 is partially lowered, all of the trays then lying above the upper end of the stem may be pushed laterally. The lateral movement of the trays is conveniently brought about by a wide ring 16 whose internal diameter is not appreciably larger than is necessary to enable

it to be moved freely up and down while embracing the stack. This ring is fastened to a sturdy block or shoe 17, through which the shaft 15 extends, thereby permitting the ring to be moved up and down and to swing about the axis of the shaft. Surrounding the shaft, underneath the lower end of the sleeve 14, is a compression spring 18 of sufficient strength to counterbalance the arm 12, the ring 16 and other parts associated therewith. The parts are so proportioned that the plane of the lower edge of the ring is slightly above the upper end of the stem 11, so that whenever the lower edge of the ring is at or slightly above the top of one of the trays, all of the trays overlying the latter will be swept to one side when the ring is moved angularly, without disturbing the remaining trays.

It will thus be seen that in order to select a record the stem and the ring are simply moved up or down until the lower edge of the ring is only slightly above the top of the tray in which the desired record reposes. Then upon swinging the ring laterally, a sufficient area of the desired record is exposed for playing the record. Obviously, there are many ways in which these two shifting movements may be performed. For the sake of brevity I have illustrated only a simple manually operable means for this purpose. This means, as shown, comprises an actuator in the form of a handle 19 that extends out through a window 20 in the front of the casing, high enough and wide enough to permit the needed vertical and lateral movements, respectively, of the actuator. This actuator is shown as fixed to the part 17 and it has a finger 21 extending downwardly therefrom and provided at its lower end with a projection that is entered in a deep groove or slot 22 that runs about half way around the sleeve 14. With this construction, whenever the handle is raised or lowered, the stem 11 and the ring 16 are given corresponding movements. However, when the handle is swung to the right or to the left, only the ring 16 swings while the arm 12 and the sleeve 14 remain stationary, since the projection 22 simply moves freely along the groove or slot 24.

In the case of a manually operable record changer, the indexing means may conveniently be associated with the handle. Thus, in the arrangement shown, there is a plate 25 of considerable length and breadth covering the window or opening 21, and lying against the inner side of the front wall of the casing or cabinet. This plate is held in place by means of suitable stationary guides 26 that permit it to be moved sideways and up and down. By giving the actuator or handle a rectangular shape in cross section, as in Fig. 4, and allowing the handle to extend through an opening in the plate of the same shape and no larger than needed to permit the handle to rock sideways relatively to the plate, the latter will have no appreciable turning movements, regardless of the manner in which the handle is operated. The front wall of the cabinet may be provided with a series of graduations 27 distributed along one vertical side of the opening 20; the spacings of these graduations being equal to the depth of one of the trays. Then, by providing the plate 25 with a horizontal line 28 that registers with the lowermost graduation when the parts are in position to shift all except the lower tray laterally, the vertical position of the handle or actuator for selecting any particular record is determined by

moving the handle vertically until the line on the plate registers with the graduation corresponding to that record.

After the actuator has been brought to the proper elevation to select the desired record and starts to swing laterally, any further shifting of the handle up or down until its return to its neutral position must be avoided. This can conveniently be done by an automatic lock or catch. In the arrangement shown, there is a long wide plate 29 fastened to the front wall of the cabinet not far from the handle or actuator and extending inwardly toward the turn table. Into the free vertical edge of this plate are cut a series of slots 30, as best shown in Fig. 9, corresponding in number to the trays that can be employed at one time, spaced between centers a distance equal to the depth of one of the trays. Fixed to the sleeve 14 is a long curved arm 31 that extends partially around and near the stack of trays. Projecting down from this arm, as best shown in Fig. 2, is a short lug 32 near the handle or actuator 19, while a much longer lug 34 extends down beside the notched end of the bracket or plate 29. A dog, in the form of a long bent bar 35, extends through and is slidably supported by these two lugs with one end in contact with the side of the finger 21 on the handle or actuator. A light spring 36 normally holds the dog in engagement with the finger 21. At the opposite end of the dog is a lip 37 which overlaps the marginal portion at the notched end of the plate or bracket 29 so that whenever the lip registers with one of the notches and is otherwise free to do so, the spring 36 pulls the dog lengthwise until the lip enters that notch. The parts are so proportioned that the lip on the locking dog registers with the lowermost notch when the actuator is in position to select the lowermost record in the stack.

Normally, when the stack is intact and the actuator therefore occupies the neutral position illustrated in full lines in Fig. 1, the locking dog is held clear of the stationary notched member; but, when the handle or actuator starts to swing in the clockwise direction as viewed in Fig. 1, the spring 36 causes the dog to follow along with the handle or actuator and thus bring its lip into the notch corresponding to the record which has been selected. In this manner the shifting mechanism is locked and remains locked against vertical movement until the actuator is returned to the starting point.

The shifting of that part of the stack of trays above the selected record is accomplished by swinging the actuator or handle 19 laterally through an acute angle, namely from the full line position in Fig. 1 to the broken line position. This carries the upper part of the stack far enough toward the right, as indicated in broken lines in Fig. 1 and in full lines in Fig. 6, to permit the usual stylus to make its record-playing sweep inwardly from the periphery of the selected record.

Some means must be provided to support the shifted trays so as not to interfere with the free rotation of the phonograph table. To this end I have mounted on the arm 31 a pair of rollers 38, rotatable about horizontal axes and having their highest points at or slightly above the plane of the flat rim face 9 of the tray that contains the selected record. When one or more trays are swung laterally by the ring, the lowermost tray engages and rides upon these rollers until

it reaches and slides over a lug or little post 39 rising from the arm 31 about midway between the two wheels. In this way the shifted trays are supported by a three-point bearing. The parts are so proportioned that the center of gravity of the part of the stack that is skimmed from the remainder crosses a line connecting the two wheels; thereby making the support a stable one. If the tops of the wheels are a little higher than the top of the uppermost tray remaining on the turntable, the tray or trays that are moving laterally are raised a little clear of the tray or trays on the turn table. If the tops of the wheels are in the plane of the top of the tray containing the selected record, the bearing face of the lug or post 39 must be a little lower so that the part of the stack that is shifted laterally may tilt a little after its center of gravity passes across the line connecting the wheels and thus raise the side overlying the trays on the turn table sufficiently to stand clear of the latter. In either case the turn table is left free to turn without interference from the shifted trays.

The tone arm 40 is carried by a third arm or bracket 41 fixed to and projecting from the sleeve 42. In the arrangement shown, and best shown in Fig. 8, there is a vertical sleeve 42 provided near the lower end with a circumferential groove 44 in which are engaged the two sides of a jaw 45 in the free end of the arm or bracket 41. This sleeve surrounds and is movable on a stationary vertical rod or shaft 46. The base end of the tone arm loosely embraces the member 42 and is connected thereto by a horizontal hinge pin 47 passing through the same and through an ear 48 on the member 42. Therefore the tone arm may move bodily up and down with and may rock up and down relatively to the arm or bracket 41, and it may swing about the vertical shaft or rod 46.

A link 49 extends between points on the tone arm and on the arm 41, both remote from the shaft or rod 46. This link has therein, at one end, a long slot 50 and near the other end a shorter slot 51. Headed pins 52 and 54 extend through these slots into the tone arm and the arm 41, respectively. A light tension spring 55 is fastened at one end to the pin 54 and at its other end to the link at 53 so as to tend constantly to hold the link in such position that the pin 54 lies in the inner end of the slot 51, as in Fig. 6. The parts are furthermore so proportioned that when the free end of the tone arm bears against the side of a stack of trays on the turn table, as it normally does when the phonograph is idle, the pin 52 lies in the outer end of the slot 50 as indicated in Fig. 1. This last named condition can only be brought about by stretching the spring 55 until the pin 54 is in the outer end of the slot 51. Therefore, upon shifting laterally that part of the stack of trays against which the tone arm bears, the spring 55 contracts and pulls the tone arm around until the stylus 56 is positioned over the playing field of the selected record; the parts being so proportioned that the tone arm is always moved, along with the actuator or handle 19, so as to be positioned a little higher than the tray containing the selected record, in making a selection. It only remains, therefore, to lower the tone arm to bring the stylus into the sound track, in order to play the selected record upon starting the motor.

The tone arm is held in an idle position, with the stylus raised, by a weight 57 which rests on

top of the rear end of the arm behind the hinge axis, as indicated in Fig. 7. When this weight is lifted, as in Fig. 8, the stylus end of the arm drops down into working position on the record, if it be over a record. The weight conveniently may be or form part of the movable armature of an electromagnet, the coil 58 of which may be fastened to the upper part of the sleeve 42. When the coil is deenergized, the weight rests on the tone arm; but, upon energizing the coil, the weight is lifted and the tone arm is left free to swing down into playing position.

After the selected record has been exposed it is necessary to energize the coil 58 and the motor and, after the record has been played, to stop the motor and deenergize said coil to permit the stack of records to be restored and the tone arm to be swung back without scratching the record. I have therefore provided a simple control system in which this cycle, after being initiated by the operation of the handle 19 or other actuator, is completed and cannot begin again until the actuator has been moved into its "off" position and a selection again made. In the arrangement illustrated, there is a normally open switch 59 mounted on the inside of one side wall in such a location that the ring 16 will engage the same and close it whenever swung laterally as indicated in dotted lines in Fig. 1 and in full lines in Fig. 6. While the ring usually carries with it one or more trays when swung laterally, it does not do so, of course, when the topmost record is to be played; but the ring must swing over to close the switch 59 and allow the tone arm to move across the record. There is a second switch 60, mounted on the arm 41 and normally closed, as shown in Fig. 1. On the tone arm is a laterally projecting pin 61 which, when the tone arm has swung in toward the center of a record as far as it needs go, strikes a projecting end 62 of the movable arm of switch 60 and opens the same, as shown in Fig. 6. The switches 59 and 60 are shown in Fig. 10 as being in series with each other, the motor and the magnet coil 58. It will be seen that with this arrangement both switches must be closed in order to play a record. Therefore, although the switch 60 is normally closed, the electromagnet, as well as the motor, remains de-energized until the pusher ring is swung to one side of the cabinet to close switch 59.

A complete cycle of operations is extremely simple. Having chosen a record to be played, the operator moves the handle (in the case of a manually-operated actuator) up or down until the marker on the plate 25 registers with the graduation corresponding to that record. He then swings the handle toward the left, causing it to be locked against further vertical movement in either direction, until the pusher ring 16 closes the switch 59. Unless it be the uppermost record that is to be played, the ring carries with it one or more records, namely all that lie above that which has been selected. In the meantime the little spring 55, pulling on the tone arm, has caused it to swing inwardly a short distance over the exposed record. This preliminary movement of the tone arm is limited by the length of the slot 51. Up to this time the stylus has been held up so as not to touch the record. However, as soon as the switch 59 closes, the motor starts, causing the turn table to rotate, and the coil 58 of the electromagnet is energized, raising the weight 57 and permitting the end of the tone arm carrying the stylus to drop until the stylus en-

gages the record. Thereafter the stylus follows along the sound track in the record in the usual way. During one or two turns of the turntable, following the end of the recording, the pin 61 on the tone arm opens the switch 60, deenergizing the coil 58 and stopping the motor. As soon as the coil 58 is deenergized, the weight 57 drops down on the tone arm and causes it to rock in the direction to raise the stylus clear of the record and above the top of the tray in which the record lies. Thereafter nothing further happens until the operating handle is shifted back to its off position to restore the pusher ring and such records as may be surrounded thereby into coaxial relation to the record or records remaining on the turn table. At the same time the tone arm is pushed out beyond the periphery of the stack by the pusher ring. The cycle may then be started anew whenever another record is to be played. It should be noted that the stem 11 is compelled to rotate with the turn table although it may move up and down relatively to the same; the stem being shown as having therein a longitudinal keyway 63 into which projects a key 64 carried by the hub 4 of the turntable. Thus the stem can exert no retarding influence on the rotation of records on the turntable. This arrangement is made possible by the fact that the stem can rotate freely in the jaw 45 but must always remain in the same vertical position relative to the latter.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. The combination with the turntable of a phonograph, of a plurality of shallow containers for flat-lying records open at the top and adapted to be arranged in stack formation on the turntable, a tone arm beside and in position to engage the containers, an actuator movable in two directions transverse to each other, a device located above the turntable and movable in the vertical direction and laterally, the device having parts to engage the side of a stack of containers to shift all of the containers overlying a selected record to expose at least a part of the same; and connections between the actuator, said device and the tone arm to cause said device and the tone arm to be moved vertically when the actuator is moved in one of said directions and said device to be shifted laterally when the actuator is moved in the other of said directions.

2. The combination with the turntable of a phonograph, of a plurality of shallow containers for flat-lying records open at the top and adapted to be arranged in stack formation on the turntable, of a device in position to surround the stack, a second device a little below the first device to hold the containers that are at a lower level than the lower edge of the first device centered on the turntable, and means to move said devices up and down in unison with each other to vary the number of containers that are held by the second device and for shifting the first device laterally to expose at least a portion of the record in the uppermost container that is being held by the second device.

3. The combination with the turntable of a phonograph, of a plurality of shallow containers

for flat-lying records open at the top and adapted to be arranged in stack formation on the turntable, of a wide ring to surround the stack, a vertical rod adapted to extend up through the turntable and the containers and terminating a little below the first device to hold the containers centered on the turntable, and means to move said ring and said rod up and down in unison with each other to vary the number of containers that are penetrated by the rod and for shifting the ring laterally to expose at least a portion of the record in the uppermost container that is being held centered by the rod.

4. The combination with the turntable of a phonograph, of a plurality of shallow containers for flat-lying records open at the top adapted to be arranged in stack formation on said turntable, of a vertically movable member beside the turntable, a tone arm mounted on said member, elements on said member for supporting containers independently of the turntable, an actuator for raising and lowering said member, said actuator being movable in a transverse direction on said member, and means connected with the actuator to shift all of the containers overlying a selected record from the turntable to said elements when the actuator is moved in said transverse direction.

5. The combination with the turntable of a phonograph, of a plurality of shallow containers for flat-lying records open at the top adapted to be arranged in stack formation on said turntable, of a vertically movable member beside the turntable, a tone arm mounted on said member, elements on said member for supporting containers independently of the turntable, an actuator for raising and lowering said member, said actuator being movable in a transverse direction on said member, and means connected with the actuator to shift all of the containers overlying a selected record from the turntable to said elements when the actuator is moved in said transverse direction, and means to lock said member against vertical movements during transverse movements of the actuator.

6. The combination with the turntable of a phonograph and the motor for rotating the same, of a plurality of shallow containers for flat-lying records open at the top adapted to be arranged in stack formation on said turntable, of a vertically movable member beside the turntable, a tone arm mounted on said member for lateral swinging movements and for rocking movements to raise and lower the tone arm relatively to a record on the turntable, elements on said member for supporting containers independently of the turntable, an actuator for raising and lowering said member, said actuator being movable in a transverse direction on said member, a device connected to the actuator to shift all of the containers overlying a selected record from the turntable to said elements when the actuator is moved in said transverse direction, an electromagnet to control the rocking movements of the tone arm, a circuit for energizing the motor and the electromagnet and two switches in said circuit, one of said switches being in position to be closed by said device at a predetermined point in its record-shifting movement, and the other switch being in position to be opened by the tone arm when the arm reaches a predetermined position relative to the center of a record being played.

EARLE G. HENRY.
